VIBRATION DAMPENING SPLICE

Leland C. Torell and William E. White, Bethlehem, Pa., assignors to Bethlehem Steel Company, a corporation of Pennsylvania

Application August 17, 1944, Serial No. 549,936

9 Claims. (Cl. 57—142)

1

Our invention relates generally to the forming of loops or eyes in the ends of multiple strand guy wires, cables, and the like, and more particularly to a means and method of fastening the returned end, in making said loops, to the main guy wires.

One of the objects of our invention is to provide a splice or connection between the end of a guy wire and its body which possesses vibration dampening characteristics.

Another object of our invention is to provide a novel splice or connection between wire cables which will connect said cables so that they possess vibration dampening characteristics.

Other objects and advantages will be more fully understood upon reference to the specification and accompanying drawings, in which

Figure 1 is a plan view of one form of our invention showing a looped wire cable with the wires of the returned end cut to different lengths;

Fig. 2 is a plan view showing a tie wire fastening the returned end to the main body of the cable shown in Fig. 1; and

Figs. 3, 4, 5 and 6 are plan views showing an alternative form of the invention shown in Figs. 1 and 2.

Referring now to the drawings more in detail, 10 is a wire cable having a plurality of wire strands 11, 12 and 13. The terminal portions or ends of the strands 11, 12 and 13 are not coincident but are shown cut to different lengths, strand 12 extending a short distance beyond strand 11, and strand 13 extending a short distance beyond strand 12. The cable 10 is shown returned upon itself forming a loop or dead end 14, the end portion 15 of the cable being in engagement with the main body portion 16 of the cable. In the form of our invention shown in Figs. 1 and 2, a tie wire 17 is then wound or served tightly in a close lay helix 18 around the end portion 15 and body portion 16 of the cable. The close lay helix 18 extends from immediately adjacent the loop 14 to a point adjacent the end of strand 11. From this point on the winding of the wire 17 is continued in a broad lay helix 19 about the cable 10 to a point on the main body portion 16 of cable 10 shortly beyond the end of the last remaining strand 13.

In the form of our invention shown in Figs. 3 to 6 inclusive, the cable 10 after being returned upon itself to form a loop 14 is served or wound with a tie wire 20 in a close lay helix 21 around the end portion 15 and body portion 16 of the cable 10. When helix 21 is completed, strand 11,

2

the end of which extends a substantial distance beyond the end of the close lay helix 21, is wrapped in a broad helix 22 about body portion 16 of cable 10 and strands 12 and 13. When this is completed, as shown in Fig. 4, strand 12 is wrapped in a broad helix 23 about the body portion 16 and strand 13 as shown in Fig. 5. The assembly as shown in Fig. 6 is completed by wrapping the last strand 13 in a broad helix 10 around the body portion 16.

The gradually decreasing reenforcement obtained by cutting the wires of the return portion 15 of the cable 10 to different lengths as shown on the drawings, will prevent sharply localized stresses, and either by serving tie wires 17 first in a closely laid helix 18 for holding strength and then in a gradually broader lay helix 19 to the end of the last wire 13 of return portion 15, as shown in Figs. 1 and 2, or by serving wire 20 in 15 a closely laid helix 21 for holding strength and then serving the end wires 11, 12 and 13 individually in broad helices as shown in Figs. 3, 4, 5 and 6 and as described heretofore, vibration dampening is accomplished with effectiveness and 20 in a manner unknown in the prior art.

Our invention is particularly useful for fastening long guy wires or cables to anchoring devices and the like. In installations of this sort, vibrations or bending of the cable resulting from wind, etc. is a serious problem. Our improved assembly, as shown on the drawings, is designed to prevent sharply localized bending stresses, thus greatly minimizing the damage to the cable from 25 said vibrations.

While we have shown our invention in a plurality of forms, it will be obvious to those skilled in the art that it is not so limited, but is susceptible of various other changes and modifications without departing from the spirit thereof, and we 30 desire therefore, that only such limitations shall be placed thereon as are imposed by the prior art or as are specifically set forth in the appended 40 claims.

Having thus described our invention, what we 45 claim as new and desire to secure by Letters Patent is:

1. A vibration dampening cable splice comprising two multiple-strand cables, one of said cables having strands of different lengths providing an 50 end portion of varying thickness, and means comprising a tie wire binding said end portion of said cable to the other cable.

2. A vibration dampening cable splice comprising two multiple-strand cables, one of said cables comprising an end portion having strands of ap-

preciable different lengths, and a tie wire binding said cables together adjacent said end portion in a close-lay helix and over said strands of different lengths in a broad-lay helix.

3. A vibration dampening cable splice comprising two multiple-strand cables, one of said cables comprising an end portion having strands of different lengths, a tie wire binding a portion of said end portion to the other cable, and said strands of different lengths binding the remainder of said end portion to said other cable.

4. A vibration dampening cable splice comprising two multiple-strand cables, one of said cables comprising an end portion having a short strand, a medium-length strand, and a long strand, a tie wire binding a portion of said end portion to the other cable, said short strand of said end portion binding said medium-length strand and said other cable, said medium-length strand of said end portion binding said long strand and said other cable, and said long strand binding said other cable.

5. A vibration dampening cable splice for a multiple-strand cable having a body portion and an end portion returned upon said body portion to form a loop, said splice comprising said body portion and said end portion, said end portion comprising strands of appreciably different lengths terminating at different points along said body portion, and a tie wire binding said strands of different lengths to said body portion intermediate said different points.

6. A vibration dampening cable splice for a multiple-strand cable having a body portion and an end portion returned upon said body portion to form a loop, said splice comprising said body portion and said end portion, said end portion comprising strands of appreciably different lengths terminating at different points along said

body portion, and a tie wire binding said end portion to said body portion in a close-lay helix adjacent said loop and over said strands of different lengths in a broad-lay helix from said close-lay helix to the end of said strands.

5. A vibration dampening cable splice comprising a multiple-strand cable having a body portion and an end portion returned upon said body portion to form a loop, said splice comprising said body portion and said end portion, said end portion comprising strands of different lengths terminating at different points along said body portion, a tie wire binding a portion of said end portion to said body portion and said strands of different lengths binding the remainder of said end portion to said body portion.

10. A vibration dampening cable splice comprising a multiple-strand cable having a body portion and an end portion returned upon said body portion to form a loop, said splice comprising said body portion and said end portion, said end portion comprising a short strand, a medium-length strand, and a long strand, said strands terminating at different points along said body portion, a tie wire binding the portion of said end portion adjacent said loop to said body portion, said short strand of said end portion binding said medium-length strand and said long strand and said body portion, said medium-length strand of said end portion binding said long strand and said body portion, and said long strand binding said body portion.

15. A vibration dampening splice comprising two members, one of said members comprising an end having portions of different cross-section, and a tie wire binding said portions of different cross-section to the other member.
